TOE PLEDGET

Sol H. Zeve, Bronx, N. Y.

Application September 28, 1950, Serial No. 187,162

2 Claims. (Cl. 128—81)

1

This invention relates to toe pads or pledges, and particularly to articles of this character, for placing between the toes of a human foot to prevent irritation or to alleviate irritated conditions which have already developed.

In this modern age the disease known as athlete's foot is a common ailment and one which is difficult to cure. Numerous products are on the market for curative purposes but their success is sporadic and uncertain and a remedy which is effective for one person is ineffective for another. Slight irritation between the toes caused by perspiration and accumulated debris, even in the absence of fungi, causing ringworm or athlete's foot, is a cause of ill-smelling feet and severe itching which, if protracted, may result in aggravated infection such as athlete's foot and similar diseases.

I have discovered that whereas expensive and complicated remedies have been proposed and used, it is possible to guard against the occurrence of irritation and infection by the use of a simple and inexpensive product in the form of a soft, separating medium disposed between the toes and anatomically molded and contoured to fit the spaces therebetween. Such a separator may or may not be medicated and is highly effective to either anticipate and prevent the occurrence of irritation or infection, or alleviate such infection once it has occurred.

The object of the invention is, therefore, to provide an anatomically molded pad or pledge capable of separating the toes and preventing irritation of the same.

A further object of the invention is to provide a simple non-irritating disposable separator which can be treated to perform a medicating action while assisting ventilation between the toes.

Still another object is to provide a pledge which can be worn with complete comfort.

Numerous other objects and advantages will be evident as the following specification is read in conjunction with the accompanying drawing in which

Figure 1 is a top plan view of a portion of a human foot with pads or pledges embodying the present invention disposed between certain of the toes.

Figure 2 is a detailed view showing one side of the pledge, and its relation to one of the adjacent toes.

Figure 3 is a view similar to Figure 2 looking from the opposite direction.

Figure 4 is a bottom plan view of a portion of

2

a human foot showing pledges of the present invention disposed between all of the toes of the foot.

Figure 5 is a section on line 5—5 of Figure 1.

Figure 6 is a detailed view of a contoured pledge embodying the present invention looking from one side thereof.

Figure 7 is a bottom view of the pledge shown in Figure 6.

Figure 8 is a section taken on line 8—8 of Figure 6.

Figure 9 is a side view of the pledge similar to that shown in Figure 6, but of smaller size.

Figure 10 is a section on line 10—10 of Figure 9, and

Figure 11 is a bottom plan view of the pledge shown in Figure 9.

Referring to the drawings, reference character 12 designates a human foot having a normal toe structure in which the great toe is designated 13, the second toe 14, the third toe 15, the fourth toe 16 and the little toe 17. Interposed between the great toe 13 and the second toe 14 is a pad or pledge 18 of the present invention, and preferably composed of a soft pliable absorbent material such as cotton.

The essential characteristics of the material are that it be soft and non-irritating to the skin in the inter-digital spaces, and that it be absorbent not only to perspiration which may collect between the toes, but also to any medication materials which are applied to it. While a soft fabric material having the characteristic of cotton is preferable, the invention is by no means limited to this particular material as numerous natural or synthetic products will be found useful in practicing the invention.

By way of illustration Figure 1 shows two pledges 18 only in position, but it will be obvious that any number may be used depending upon the condition to be met.

A typical configuration of a normal human foot with pledges disposed in all of the interdigital spaces is shown in Figure 4.

In utilizing the invention to the best advantage the pads or pledges are molded and preshaped to fit accurately into the inter-digital spaces of a normal human foot. They are, however, of such material that if the inter-digital spaces of the wearer differ somewhat in shape from those of an absolutely normal foot they will conform to and become molded to accurately and comfortably fit the feet of the wearer. In this way maximum comfort is obtained at a

minimum cost, because it is not necessary to have a special fitting for each individual.

It appears to be a popular misunderstanding that human feet vary greatly in configuration, while it is a fact that such is not the case. The size of the feet of various individuals may vary greatly but the interdigital spaces of the feet present substantially the same configuration varying only in size where the foot is normal, that is, free from malformation at birth or from injury. This will be evident from Figures 2 and 3, showing a pledge viewed from opposite sides in the two figures. It will be observed that the pledge 18 has at its forward or outer portion and also at its top and bottom, a configuration approximating that of the toe against which it presses. The rearward portion of the pledge on the other hand is more or less triangular as indicated at 19. Likewise the bottom portion 20 is of somewhat triangular form so that the area between these two parts presents a peculiar curved formation where it contacts the root of the interdigital space designated 21 in Figure 2. Thus it is possible to provide pledges of the same configuration yet of varying size, which will assume accurately the contour of the foot of the wearer without detailed preshaping operations. When placed in position the pledge becomes anatomically molded to the precise shape of the foot area of the wearer.

Reference to Figure 4 will indicate how these pledges look when they are subjected to lateral pressure from the adjacent toes, and to upward pressure from the surface against which the foot carrying these pledges rests. Again viewed in cross section the pledges appear as in Figures 5, 8 and 10, approximating a dumbbell shape, the abruptness of the curvature depending somewhat upon the resiliency of the material and its initial thickness, and also depending upon the toe formation of the wearer.

While it has been indicated above that the pledges of the present invention may or may not be medicated, it will be preferable in most instances to perform such medication and such is contemplated.

Inasmuch as irritated interdigital spaces usually result from an acid condition, it is well to include in the antiseptic medicating material an agent capable of counteracting that condition, and it is therefore contemplated that numerous ingredients may be provided to suit particular situations. For instance the pad or pledge may be saturated or mildly treated with a deodorant, an astringent and cooling agent, or with a germicide and antiseptic fungicide. Alternately compatible materials having all of these properties may be included together.

Purely by way of illustration and without limitation to the particular material used, it has been found that representative materials suited to various conditions are as follows:

Ingredient	Function
Eucalyptol.	deodorant.
Menthol.	astringent and cooling.
Phenol.	germicial.
Salicylic acid.	antiseptic and astringent.
Zinc sulphate.	astringent.
Fuchsin (basic).	germicial-fungicidal.
Boric acid.	antiseptic.

In the case of the application of the pledges to the feet of a person seriously afflicted with athlete's foot, the use of a specific medication may be desirable. An example of such a medication is as follows:

	Per cent
Zinc undecylenate	15
Undecylenic acid	3
Talc U. S. P.	82

The above examples are given purely by way of illustration and not by way of limitation.

It will be understood that the pledges of the present invention can be tinted if desired to suit any particular situation. For example they may be flesh-tinted where they are to be worn with open toed shoes, and the sizes may be varied to suit various sizes of feet. They are initially formed and shaped to suit the general contour of a normal foot and then are molded to a precise fit when placed in position between the toes of the wearer. It will be understood that these pads are more or less wedge-shaped in formation so as to enter the web or interdigital space between the toes without causing skin irritation, and yet providing sufficient separation of the toes to prevent friction. They may or may not be treated with a medication and will be anatomically molded to a precise fit when they have been worn for a short period.

Thus it is evident that I have provided a simple but effective means of not only treating skin diseases between the toes but preventing the same by eliminating the factors which lead to irritation and disease. The invention is applicable not only to serious conditions which have developed, but also in anticipating such conditions, and in eliminating completely and simply all of the undesirable characteristics of malodorous feet.

Having thus described my invention what is claimed is:

1. A medicated toe pledge comprising a thin elongated absorbent member having the approximate outline of a human toe, the sides of said member being provided with a hollow approximating the shape of an ellipsoidal concavity and the rear of said member being provided at its upper end with a rearwardly extending curved portion.

2. A toe separating pledge comprising a thin flat absorbent body shaped to fit between the toes of a human foot, and having a rearward portion fitting into the root of said space and holding the toes apart, said pledge having sides provided with a hollow approximating the shape of an ellipsoidal concavity and being sufficiently pliable to be molded into the space where it lies, by the action of the toes which it separates.
